UNITED STATES PATENT OFFICE.

ARTHUR E. LANGLOIS, OF NEW BEDFORD, MASSACHUSETTS.

DESIGN FOR A PENNANT.

55,286.

Specification for Design.

Patented May 25, 1920.

Application filed May 2, 1919. Serial No. 294,334. Term of patent 3½ years.

To all whom it may concern:

Be it known that I, ARTHUR E. LANGLOIS, a citizen of the United States, residing at New Bedford, in the county of Bristol and State of Massachusetts, have invented a new, original, and ornamental Design for a Pennant, of which the following is a specification, reference being had to the accompanying drawing, forming part thereof.

The figure is a plan view of a pennant showing my new design.

I claim:

The ornamental design for a pennant as shown.

ARTHUR E. LANGLOIS.
